UNITED STATES PATENT OFFICE.

ARTHUR J. TIZLEY, OF NEW YORK, N. Y., ASSIGNOR TO EDWARD F. CALDWELL AND COMPANY, OF NEW YORK, N. Y., A CORPORATION OF NEW YORK

SHADE-HOLDER.

1,274,214.

Specification of Letters Patent. Patented July 30, 1918.

Application filed March 9, 1918. Serial No. 221,483.

To all whom it may concern:

Be it known that I, ARTHUR J. TIZLEY, a citizen of the United States of America, residing in the city of New York, borough of 5 Brooklyn, in the county of Kings and State of New York, have invented a certain new and useful Improvement in Shade-Holders, of which the following is a specification.

My invention relates to shade-holders and 10 particularly to a support for shades of the inverted globe type, the object of my invention being to improve the construction shown in the Evans *et al.* Patent 1,192,049, by rendering the locking device thereof automatic.

15 In the accompanying drawing,

Figure 1 is a section through a fixture showing my invention applied to the globe holder in one form;

20 Fig. 2 is a plan of the globe holder detached;

Fig. 3 is a broken plan of one of the supporting arms, showing the supporting finger thereof in position to permit the adjustment of the globe;

25 Fig. 4 is a side elevation thereof, showing the locking sleeve in section.

In the shade holder shown in the Evans patent above mentioned, one of the supporting arms is made in two parts pivoted together and normally held in alignment by a locking sleeve. The latter, however, is loose upon the arm and must be moved positively in both directions first to release the sections to permit them to pivot with relation to each 35 other, and thereafter again to lock the same in alignment. Moreover, when the parts are released, the globe-engaging end or finger of the arm is free to swing and does not maintain any precise relationship to the fixture 40 end of the arm, with the result that it is apt to get in the way during the adjustment of the globe on the support. By my present improvement, I provide the locking sleeve with means for automatically returning it to

45 locking position when the globe-engaging finger is swung up into operative position, and, at the same time, maintain the finger in predetermined out-of-the-way position during the adjustment of the globe on the 50 holder.

While the globe holder may be applied to fixtures of various sorts and may be supported in any suitable way, I have here indicated it applied to a lamp socket 10, on the 55 casing of which is secured an ordinary globe

or shade holder 11, carrying set screws 12. The shade for the lamp 13 is here shown as a globe 14 of inverted type, and is supported by the arms 15, 16, and 17 of the holder to which my invention particularly relates. 60 These arms are here shown as heavy wire rods fixedly secured at their upper ends to a channel ring 18 adapted to be inserted within the skirt of the shade holder 11 and engaged by the set screws 12 to hold it in position. The two arms 15 and 16 are rigid throughout their length. The arm 17 is divided, and the outer free end thereof forms a globe-engaging finger 19, pivoted thereto at 20. A lap joint between the sections of the 65 arm is formed by cutting away the pivoted ends of the arm sections, and the end of the finger 19 is beveled at 21 to permit the finger to swing downward as indicated in Fig. 4, but forming a stop bearing against a similar incline 22 on the fixed end 17 to prevent the upward swing of the finger 19 and halting the latter when in alignment with the fixed end 17. 70

In order to hold the finger 19 in alignment with the fixed end of the arm 17, I provide a locking sleeve 23, sliding on the fixed portion 17 of the arm and abutting at one end against the heads of the pivot pin 20 which prevents the sleeve from running 80 down the finger 19. The locking sleeve 23 is of greater diameter than the arm 17 and forms a housing for a coil spring 24, one end of which is offset and passed into a hole 25 in the arm 17, while the other end thereof abuts against a shoulder 26 formed in any suitable way at the end of the sleeve adjacent the joint between the arm sections. The end of the sleeve is preferably rounded or beveled at 27 to facilitate the automatic 85 action of the locking sleeve when the finger 19 is swung up into globe-engaging position. 90

The operation of the device is readily understood. Under normal conditions, the 100 locking sleeve holds the finger 19 in alignment with the arm 17 as indicated in Figs. 1 and 2. In order to adjust the globe 14 on the holder, the locking sleeve 23 is slid up the arm 17 until the finger 19 is released and swings down to the position indicated in Figs. 3 and 4. The sleeve 23, being now released, returns under the action of its spring 24 and bears against the finger 19, holding the latter down with spring pres- 105

sure in out-of-the-way position. The arms 15 and 16 are now engaged in the groove 28 in the upper margin of the globe 14, and the latter swung up to proper position. The 5 only action then necessary to complete the engagement of the globe by the holder is to swing up the finger 19 into alinement with the arm 17. On its upward movement, the beveled end 21 of the finger 19 bears against 10 the bevel 27 on the locking sleeve 23 and forces the latter up the arm 17 against the action of its spring 24. As soon as the finger 19 comes in alinement with the arm 17, the sleeve 23 is automatically returned by 15 its spring 24 into locking engagement therewith and rests against the heads of the pivot pin 20. The finger 19 is thus held rigidly in supporting position.

23 The improvement thus provided does not alter in any way the appearance of the support, and has the advantages above pointed out, in addition to those disclosed in the Evans patent. The manner in which the 25 arm 17 is secured to its supporting ring is immaterial, as is also the contour of the arm and the shape of the supporting finger, and I do not limit my claim of invention to the precise form of construction illustrated.

26 I claim:

1. In a shade holder an arm, a shade-engaging finger pivoted thereto but movable to out-of-the-way position during the adjustment of the shade on the holder, and a 35 spring pressed locking member holding said finger in both positions, together with means automatically displacing said locking device as the finger is moved to shade-engaging position but thereafter releasing said locking device to permit it to return under the ac-

tion of its spring to locking position and 40 thus hold the finger in shade-engaging position.

2. In a shade holder a supporting arm having jointed thereto a shade-engaging finger, in combination with a displaceable 45 spring pressed locking member engaging said arm and finger to hold the latter in normal shade-engaging position, and means releasing said locking member as the finger reaches its normal position to thereby permit 50 the automatic return of said member to locking position under the action of its spring.

3. In a shade holder an arm, a shade-engaging finger pivoted thereto but movable to out-of-the-way position during the adjustment 55 of the shade holder, a locking sleeve mounted on said arm and engaging said finger to hold it normally in locking position, together with a cam lug on said finger engaging said sleeve to displace the same out 60 of obstructing position as the finger is brought into its normal position.

4. In a shade holder an arm having a shade-engaging finger pivoted thereto, in combination with a spring pressed locking 65 sleeve mounted on said arm and engaging said finger to hold the latter in normal position with relation to the arm, together with a cam lug on said finger automatically displacing said sleeve out of obstructing position as the finger is moved into its normal shade-engaging position.

In testimony whereof I have signed my name to this specification.

ARTHUR J. TIZLEY.
